UNITED STATES PATENT OFFICE

ROY L. CHENAULT, OF PITTSBURGH, PENNSYLVANIA, ASSIGNOR TO GULF PRODUCTION COMPANY, OF PITTSBURGH, PENNSYLVANIA, A CORPORATION OF TEXAS

PNEUMATIC PUMPING APPARATUS

Application filed January 14, 1932. Serial No. 586,684.

This invention relates to a pneumatic pumping apparatus for raising liquids from deep wells in stages and discharging such liquids in a continuous succession of slugs under a back pressure maintained on the flow line of the apparatus. More particularly, the invention is concerned with the pumping of oil from oil wells by the use of concentric strings of tubing which extend into the well, one of which strings is reciprocable to actuate a piston type valve for admitting pumping fluid to a displacement chamber in the lower part of the apparatus thereby to expel liquid which has collected from the well, and to raise such liquid to a predetermined height from which it is lifted to the pump outlet by the successive admission of pumping fluid when the valve is in its other position, the liquid being ejected from the pump in slugs, the velocity of which is retarded by maintaining the pump discharge under a back pressure; all as will be described more fully hereinafter, and as claimed.

It is an object of this invention to provide a pumping apparatus for raising liquids from deep wells in stages by the admission of a pumping fluid to the apparatus successively at different levels.

Another object is the provision of apparatus to decrease the emulsification of pumped liquids and to effect a saving of energy by maintaining a back pressure on the flow line which results in a smaller increase in velocity of the pumped liquids as they approach the top of the well and thereby reduces the turbulence at the outlet.

Other and further objects will be apparent from the following description and drawings, in which

Figure 1 is a view, partly in vertical section, showing the pump and apparatus with which it is associated in use;

Figure 2 is an enlarged detail view of the upper part of the pump mechanism with the valve in one position for pumping;

Figure 3 is a similar enlarged detail view of the upper part of the pump mechanism with the valve in the other position for pumping;

Figure 4 is a horizontal sectional view, taken along the line 4—4 of Figure 2;

Figure 5 is a horizontal sectional view, taken along the line 5—5 of Figure 2;

Figure 6 is an enlarged detail view of the lower end of the pump, in vertical section, showing a modified form of foot valve in one position of pumping;

Figure 7 is a view similar to Figure 6, but showing the modified form of foot valve in the other position of pumping.

Referring more particularly to the drawings:

A casing 10 extends into the bore of a well and encloses two concentric strings of tubing 11 and 12, the outer of which is composed of a displacement chamber 13 and a valve cylinder 14 in axial alignment and connected to the tubing 11 by a nipple 15. This string is run first into the well to a point where the displacement chamber is submerged in the liquid which is to be pumped.

The inner string of tubing 12 is next lowered into the well within the string 11. The tubing 12 comprises an eduction pipe 16 which is attached to a piston valve 17, the valve, in turn, being connected to the tubing 12 by a nipple 18 and threaded sleeve 19.

The foot valve assembly 20 may also be lowered into position in the seat 21 which forms the end of the displacement chamber, by means of the rod 22 which is attached to the valve cage and which extends up into the eductor pipe 16 to be slidably received therein but prevented from removal by the head 23 which cannot pass the projection 24 in the eductor pipe. This arrangement permits all working parts to be removed for repairs or replacement by pulling the single inner string of tubing.

The foot valve assembly 20 which is shown in Figure 1 and which includes a ball check valve may be replaced by a foot valve of the type shown in Figures 6 and 7 wherein a pipe 25 is connected to the eductor pipe 16 by a sleeve 26 and is closed at its end by a plug 27 which is tapered to permit installation and removal of the pipe 25 with the inner string of tubing.

The pipe 25 has a close, sliding fit in the

- seat member 21 and is slotted at 28 so that when the inner tube string is lowered to the position shown in Figure 6 communication is established between the displacement chamber 5 and the interior of the well, whereas when the string is raised to the position shown in Figure 7, while the displacement chamber is being emptied, communication between the displacement chamber and well is cut off.
- The piston valve cylinder has inner and outer walls defining separate annular spaces 29 and 30 above and below the connecting web 31, and the spaces, respectively, communicate with horizontal ports 32 and 33 which open into the interior of the cylinder. Exhaust ports 34 (Figures 2, 3 and 5) extend horizontally from the interior of the valve cylinder to the space between the outer tube string 12 and the well casing. A radial series of such exhaust ports is provided as is shown in Figure 5.
- The piston valve 17 is equipped with piston rings or other suitable packing for making a tight seal between the various valve ports and the two ends of the valve, these rings or packings defining annular spaces 35 and 36 for connecting the various valve ports. Ports 37 connect the annular groove or space 36 with the hollow interior of the piston.
- A check valve 38 is provided and may be located either in the eductor pipe 16, as shown, or in the piston valve at any point below the ports 32.
- A stuffing box 39 is provided at the top of the well which forms a tight seal between the two strings of tubing and allows the inner string to be raised and lowered sufficiently to operate the piston valve 17.
- Any convenient lifting mechanism may be employed for raising and lowering the tube string 12. The preferred mechanism, however, is shown in Figure 1 and it comprises a pneumatic power cylinder 40, controlled by an automatic timing valve 41 which admits compressed air or gas to the cylinder for raising the tubing 12, and, alternately exhausts the motive fluid from the cylinder to the atmosphere allowing the tubing to lower by gravity. The time interval for raising and lowering the tubing is controlled by regulation of the automatic valve. A mechanical or hydraulically operated lifting mechanism may be used in place of the pneumatic apparatus shown, if desired.
- In the illustrated system a compressor 42 receives gas or compressed air from a separating chamber 43 which is maintained under pressure, and forces such fluid through pipe 44, past valve 45, into the space between tube strings 11 and 12 within the pump. A branch conduit 46 extends between the pipe 44 and the cylinder 40 and has therein valves 47 and 48 and a pressure reducing valve 49.
- Gas and liquid withdrawn from the well flows through the outlet 50 into the separator 43. A flexible connection 51 is provided in the outlet to permit reciprocation of the inner tube string.
- In assembling the pump the displacement chamber 13 is lowered on the outer string of tubing 11 until it is in the well liquid. It will fill with liquid to the level of liquid in the well. The inner string of tubing 12 is then lowered until the piston valve 17 is in its working position in the valve cylinder 14. This position may be determined by noting the distance between the lower end of the eductor pipe 16 and the cage of the foot valve 20, when the piston valve is in its proper working position, before the device is installed in the well. The inner string is lowered until the lower end of the eductor pipe rests on top of the lower valve cage and is then raised the necessary distance to bring the piston valve into its proper working position, and the tube string is finally connected to the lifting device at the surface of the well.
- In operation, compressed air or gas is admitted to the lifting apparatus by opening the valves 47, 48, and the pressure applied to the hoist piston is regulated by the reducing valve 49. When the timing valve 41 is set to admit compressed air or gas to the hoist the inner string of tubing is raised sufficiently to lift the piston valve 17 to the position shown in Figure 3. In this position the annular space between the two strings of tubing communicates with the displacement chamber 13 by means of the vertical passages 29, 30, the horizontal ports 32, 33 in the cylinder wall, and the annular space 35 around the piston valve.
- Compressed air or gas is admitted to the space between the tube strings by opening the valve 45, and then flows down around the piston valve to the displacement chamber where it exerts a downward force on the liquid trapped therein, seating the valve 20 and forcing the oil up through the eductor pipe 16 and past the check valve 38 toward the surface through the inner string of tubing.
- After sufficient time has elapsed for the displacement chamber to be emptied of its charge of oil the inner string of tubing is lowered by shifting the timing valve to the exhaust position shown in Figure 1, thus relieving pressure below the power piston in chamber 40, through the medium of which the inner tube string is reciprocated. The piston valve 17 is, thus, returned to its lower position as shown in Figures 1 and 2 and the pressure in the displacement chamber is relieved by exhausting the gas to the well casing 10 through the vertical passage 30, the ports 33, the annular space 35 around the piston valve, and the exhaust ports 34 (Figures 2 and 5) leading through the cylinder wall.
- When the piston valve is lowered, the an-

- 5 nular space 36 between it and the cylinder wall is opposite the ports 32 so that compressed air or gas is admitted to the interior of the piston valve through the ports 37 and continues to lift the oil which has been raised previously to a level above the check valve 38, at the same time the displacement chamber is being exhausted and refilled with a new charge of well fluid.
- 10 10 After sufficient time has elapsed for the gas pressure to exhaust from the displacement chamber and a new charge of oil to flow in through the check valve 20, Figure 1, or the slot 28 in pipe 25 as shown in Figure 6, the piston valve is again raised by raising the inner string of tubing whereby the check valve 20 is seated against return flow of liquid from the displacement chamber, or, if the modified form of valve is used, the slotted pipe 25 will be raised to the position shown in Figure 7 to cut off communication between the well and the displacement chamber to prevent back flow of liquid. Another charge of oil is then forced up the eductor pipe and into the inner tubing, and the cycle is repeated. Thus, a number of separate slugs of oil, separated by columns of compressed air or gas, may be put into the inner string or flow line, and the admission of a new charge does not interfere in any way with the progress of the slugs of oil and gas traveling up the flow line to the well outlet.
- 15 15 The ability to exhaust the displacement chamber and pick up a new charge of oil before preceding charges reach the surface is an important feature of this apparatus, especially where fluid levels are low and the well depth is great. With low fluid levels a short displacement chamber must be used, and the volume of fluid picked up per stroke is necessarily small in wells of small diameter. If this relatively small slug must be brought to the surface from a great depth before the displacement chamber can be exhausted and refilled with oil, the rate of production is necessarily low and the gas or air consumption is high.

20 20 In the use of the present invention, however, as many slugs as desired may be put into the flow line by regulating the frequency of operation of the piston valve, by adjusting the timing valve, or by varying the air or gas pressure to change the velocity of flow up the discharge line.

25 25 As the slugs of oil and gas reach the surface they flow through the discharge pipe 50 and flexible connection 51 to the separator from which the oil is withdrawn through an outlet at a low point while the gas is taken off from a high point in the separator and is led back to the compressor for re-cycling. Gas exhausted from the displacement chamber to the space within the well casing may be withdrawn by a vacuum gas gathering line

or it may be conducted back to the compressor inlet.

30 30 It is seen that this method of producing oil may be utilized in wells having low fluid levels where it is impossible to use the regular gas lift system because of insufficient submergence. No back pressure is placed on the producing horizon when this apparatus is used as the gas pressure is confined within the pumping unit and not the well casing as in the case of the ordinary gas lift.

35 35 There are no "pick-up" losses such as occur in the regular gas lift as a result of gas slipping through the oil, especially in cases where the submergence is low. With this apparatus the flow of oil is accelerated by the pressure of air or gas acting downward on a fluid piston, and there is no possibility of slippage during the time a charge of oil is being accelerated and started up the flow string.

40 40 The arrangement of surface equipment shown in Figure 1 is especially desirable as it permits a back pressure to be held on the flow line and the gas separator. Operating with back pressure has advantages both from the standpoint of energy required, and the size and cost of equipment. The size of the compressor and separator equipment necessary is reduced by operating with back pressure, because when working between the same pressure difference between inlet and exhaust, the compression ratio is less when exhausting to a pressure above atmospheric than when exhausting to atmosphere. This effect is better illustrated by the following examples:

45 45 Assume that a pressure difference of 200#/sq. in. is required, between the air or gas inlet to the tubing and the inlet to the separator, to operate the pump. Then taking atmospheric pressure as 14.7#/sq. in., the compression ratio when exhausting to atmosphere is

$$\frac{214.7}{14.7} = 14.6. \quad 110$$

50 50 Operating under the same conditions, except exhausting to the separator against 50# gage pressure and supplying air or gas to the pump at 250# gage pressure, the compression ratio is

$$\frac{264.7}{64.7} = 4.1. \quad 120$$

55 55 Thus it is seen that the compressor displacement necessary to supply the volume of gas or air at the required pressure is

$$\frac{14.6}{4.1} = 3.6 \quad 125$$

60 60 times as great when exhausting to atmospheric pressure as when exhausting to a gage

pressure of 50# and supplying gas back to the compressor intake at this pressure.

This effect is greater the higher the back pressure used, and the optimum conditions will be determined by the limitations of the equipment used. Besides the reduction in compressor capacity, a further saving in compressor costs will result from the fact that a single stage compressor can be used in many cases when pumping with back pressure on the system, where two or more stages would be required when exhausting to atmosphere. Considering the example cited above, a single stage compressor could easily handle a compression ratio of 4.1 when operating with a back pressure of 50#, while a two stage compressor would be necessary when exhausting to atmosphere with a compression ratio of 14.6.

A considerable saving in energy also results from operating with back pressure as the energy required to increase the pressure of a given mass of gas a given amount decreases as the pressure increases. Referring again to the example cited above, when compressing air from atmospheric to 200# gage pressure, the theoretical energy required per cubic foot of free air for isothermal compression is 5,676 foot pounds, while the energy required to compress 1 cubic foot of free air isothermally from a pressure of 50# gage to 250# gage is only 2,982 foot pounds. However, a greater mass of air is required in the system at the higher pressure in the ratio of the absolute pressures of the two examples, or

$$\frac{264.7}{214.7} = 1.23.$$

49

Then the net saving in energy required when operating between 50# and 250# gage pressure is $5,676 - 2,982 \times 1.23 = 2,000$ ft. lbs. per unit volume the equivalent of that occupied by a cubic foot of free air when compressed to a pressure of 214.7# abs., or

$$\frac{14.7}{214.7} = .0685 \text{ cu. ft.}$$

50

at the working pressure in either case. This represents a saving of about 35.5% in energy when operating against a back pressure of 50# gage. The saving when compressing adiabatically is about the same as for isothermal compression, although the actual energy required is greater both with back pressure and when exhausting to atmosphere.

A further advantage of back pressure is that resulting from the smaller increase in velocity as the fluid being pumped approaches the top of the well, since the expansion ratio is much less when pumping

against any considerable back pressure. This acceleration of the well fluid as it approaches the surface has been a source of considerable trouble in ordinary gas lift practice. The high velocities resulting from expansion of the gas as the pressure diminishes when it progresses up the flow line, greatly increases the turbulence, and trouble from emulsions in wells which are producing both oil and water. The resistance to flow also increases rapidly with the velocity. The effect of back pressure in diminishing the acceleration toward the surface is readily seen by referring again to the two examples cited. When the air or gas is exhausted to atmosphere the expansion ratio is 14.6. When exhausting to a back pressure of 50# gage the expansion ratio is 4.1 or less than $\frac{1}{3}$ that of the former case. This will result in a corresponding decrease in acceleration of the well fluid as it approaches the surface, and a more uniform velocity of flow throughout the length of the flow line.

It should be pointed out that the advantages resulting from the utilization of back pressure with this device are obtained without putting any undesirable back pressure on the producing formation. The pressure required to operate the device is confined entirely within the two strings of tubing and the displacement chamber. If back pressure on the producing sand is desired for any reason, it may be held in the casing without interfering with the operation of the device.

In cases where extremely low fluid levels are encountered, making it impossible to collect the displacement chamber full of fluid by gravity, a packer may be set at any point below the exhaust ports 34 making a tight seal between the displacement chamber, or piston valve and well casing. If the casing is then connected to a vacuum gas gathering line, the displacement chamber may be exhausted to a pressure several pounds below atmospheric and oil may be made to rise in the displacement chamber to a point several feet above the fluid level in the well, resulting in an increase in speed and efficiency of pumping.

I claim:

1. Pneumatic pumping apparatus for deep wells which comprises a displacement chamber adapted to extend into the liquid of a well, an eduction pipe extending into said displacement chamber, a source of pneumatic pressure, valve means positioned on said eduction pipe for alternately connecting said source of pneumatic pressure with the displacement chamber and then with the eduction pipe, whereby when the valve means is in one position the pressure of pneumatic fluid is directed into the displacement chamber to force liquid therefrom into the eduction pipe and upon reversal of the said valve

means the pressure of the pneumatic fluid is directed into the eduction pipe to lift the liquid in the eduction pipe to the surface of the well.

5 2. Pneumatic pumping apparatus for deep wells which comprises a displacement chamber having valved communication with the interior of a well below the surface of liquid therein, an eduction pipe extending into said 10 displacement chamber, a source of pneumatic pressure, reciprocating valve means positioned on said eduction pipe for alternately admitting pneumatic fluid under pressure first to the displacement chamber and then to 15 the eduction pipe, a valve in said eduction pipe below the point of admission of pneumatic fluid to prevent return of liquid forced from the displacement chamber, whereby in one position of the reciprocating valve means 20 the force of pneumatic fluid is directed into the displacement chamber to force liquid therefrom into the eduction pipe and past the said valve therein and in another position of the reciprocating valve the force of the pneumatic fluid is directed into the eduction pipe to lift the liquid in the eduction pipe to the 25 outlet of the well in slugs, and means for simultaneously relieving the displacement chamber of pneumatic pressure to permit its 30 refilling by liquid from the well preparatory to another cycle of operation.

3. In combination with a source of fluid under pressure, a pump comprising a displacement chamber immersed in the liquid to be pumped, a valve for admitting well liquid into said chamber but preventing its return flow into the well, a valved eduction pipe extending to a low point in said displacement chamber, a reciprocating piston type valve 40 positioned on said eduction pipe coaxial therewith, said valve serving to connect a source of fluid under pressure alternately with the displacement chamber and the eduction pipe above the valve therein, whereby 45 said fluid under pressure is first admitted to the displacement chamber to force liquid therefrom up into the eduction pipe and secondly upon reversal of said piston type valve said fluid under pressure is admitted to said 50 eduction pipe to lift the liquid to the surface of the well in successive slugs said valve also simultaneously relieving the displacement chamber of pneumatic pressure, whereby the chamber is refilled by liquid from the well 55 preparatory to another cycle of operation.

4. A deep well pump comprising a tube string divided into upper and lower ported chambers, a displacement chamber on the lower end of said tube string, an eduction pipe extending through said tube string and terminating in said displacement chamber, a piston type valve coaxial with said eduction pipe and reciprocable to alternately cover and uncover the ports in said upper and lower chambers, said eduction pipe, further, being

provided with a port communicating with the space around the piston type valve, a source of pneumatic fluid under pressure in communication with said upper ported chamber whereby, when the piston type valve is reciprocated to one position, fluid under pressure will flow through the ports in said upper chamber, around the piston type valve, and through the ports in said lower chamber into the displacement chamber, thereby to force well liquid into the eduction pipe by downward pressure upon the surface of such liquid and to substantially empty the displacement chamber, and whereby when the piston type valve is reversed, communication of fluid under pressure with the displacement chamber is cut off but is simultaneously established between the said upper chamber and the eduction pipe through the ports therein to further lift the liquid toward the surface of the well in successive slugs.

5. A deep well pump comprising concentric strings of tubing, the outer of which terminates at its lower end in a displacement chamber, a valved inlet in said displacement chamber, a piston cylinder open at both ends, supported within the outer string of tubing and spaced from the inner wall thereof by a web element, ports in the wall of said cylinder above and below the web element affording communication between the interior of the cylinder and the interior of the outer tube string, an inner tube string comprising a reciprocable outlet pipe, a hollow piston type valve coaxial therewith and reciprocable in said cylinder, and an eduction pipe extending into said displacement chamber, a plurality of enlarged piston heads forming part of said piston type valve and closely received within said cylinder, ports extending through said piston type valve between certain of the piston heads, and a check valve in said inner tube string below said ports in the piston type valve, a source of fluid pressure communicating with the space between the outer and inner tube strings, whereby upon reciprocation of the inner tube string compressed fluid will be admitted to the displacement chamber by passing through the ports on either side of the web element and around the piston type valve, thus exerting downward pressure on the liquid in the displacement chamber and forcing it up the inner tube string past the check valve therein, from which point it is lifted by fluid pressure when the position of the piston type valve is reversed to admit the pumping fluid through the ports in such valve, and means for simultaneously venting the displacement chamber to relieve it of pressure for refilling with well liquid preparatory to another cycle of operation.

6. Pumping apparatus for wells comprising an outer string of tubing, a web element dividing the said string of tubing into upper

and lower chambers, an inner string of tubing for discharging liquid from the well, a reciprocable valve carried by said inner string of tubing for establishing and interrupting communication between a source of pumping fluid and said strings of tubing, respectively, a fluid operated piston for reciprocating said valve and inner tube string, a compressor for forcing pumping fluid into the outer tube string and intermittently into the inner tube string upon actuation of the valve, a separating chamber, piping connecting the inner string of tubing with said chamber to conduct pumping fluid and well liquid from the inner string of tubing thereinto, said separating chamber being maintained under superatmospheric pressure, and piping leading from said separating chamber to said compressor, whereby the compressor and flow line of the apparatus will be maintained under back pressure.

7. A pneumatic pumping system in which no back pressure is placed on the producing horizon, consisting of two concentric strings of tubing, a stuffing box carried by the outer string of tubing to permit the inner string to be raised and lowered without leakage between the two said concentric strings, a piston type valve attached to the inner movable string of tubing, a cylinder for said valve within the outer string of tubing, a displacement chamber attached to the outer, stationary string of tubing at its lower end and extending into the well liquid, a check valve in the bottom of the displacement chamber for admitting liquid from the well, an eduction pipe extending into the displacement chamber to provide a continuous passage through the piston type valve for delivering liquid from the displacement chamber to the inner string of tubing, a check valve in the eduction pipe, means for supplying compressed gas to the annular space between the two strings of tubing, and means for admitting compressed gas to the displacement chamber from the annulus between the two strings of tubing, and means for exhausting compressed gas from the displacement chamber by vertical motion of the inner string of tubing.

8. A pneumatic pumping apparatus comprising inner and outer concentric strings of tubing, a displacement chamber at the lower end of the outer string of tubing, a flow line of less diameter than the displacement chamber, reciprocating valve means carried by the flow line for admitting compressed gas intermittently to the displacement chamber to act downwardly on the surface of liquid therein and force it into the flow line, the valve means being reciprocable to interrupt the flow of pumping fluid to the displacement chamber, whereby it may be relieved of pressure, an exhaust port from said outer string of tubing, a well casing surrounding the concentric

strings of tubing and a packing between the well casing and outer string of tubing below the exhaust port therein to permit the pressure in the casing to be reduced below atmospheric for increasing the volume of well liquid collected in the displacement chamber which extends above the normal fluid level of the well.

9. In combination with a source of fluid under pressure, a pump comprising a displacement chamber immersed in the liquid to be pumped, a stuffing box in the lower end of said displacement chamber, a hollow, ported rod extending through said stuffing box and reciprocable to establish or interrupt communication between the interior of a well and the interior of said displacement chamber, an eduction pipe extending into said displacement chamber and attached to said hollow rod, a reciprocable piston type valve coaxial with said eduction pipe to establish communication between the source of fluid under pressure alternately with the displacement chamber when the hollow rod is in position to close the displacement chamber at its lower end, and with the eduction pipe at an intermediate point therein, a check valve in said eduction pipe below such intermediate point, whereby when fluid is admitted to the displacement chamber to force liquid therefrom up into the eduction pipe, the liquid is prevented from flowing back to the displacement chamber by said check valve whereupon, when the position of said piston type valve is reversed, the column of liquid is lifted to the surface of the well in successive slugs while, at the same time, the flow of pumping fluid to the displacement chamber having been interrupted, such chamber is relieved of pneumatic pressure and, the hollow ported tube having been reciprocated simultaneously with the piston type valve, the displacement chamber is refilled with liquid preparatory to another cycle of operation.

10. Pneumatic pumping apparatus for deep wells comprising a well casing, a pipe positioned in said well casing, a piston valve and an eduction pipe positioned in said first mentioned pipe, said piston valve dividing said first mentioned pipe into an upper chamber for the reception of compressed air and a lower chamber adapted to be submerged in the liquid in the well, the piston valve adapted to alternately admit compressed air into said lower chamber and then into said eduction pipe, said piston valve exhausting air from said lower chamber into the well casing during admission of air into the eduction pipe.

11. Pneumatic pumping apparatus for deep wells comprising a pipe positioned in said well, a piston valve and an eduction pipe positioned in said first mentioned pipe, said piston valve dividing said first mentioned

- pipe into an upper chamber for the reception of compressed air and a lower chamber adapted to be submerged in the liquid in the well, the piston valve adapted to alternately admit compressed air into said lower chamber and then into said eduction pipe, said piston valve exhausting air from said lower chamber into the well during admission of air into the eduction pipe.
12. Pneumatic pumping apparatus for deep wells comprising a pipe positioned in said well and a combined piston valve and eduction pipe positioned in said first mentioned pipe, said piston valve dividing said first mentioned pipe into an upper chamber for the reception of compressed air and a lower chamber adapted to be submerged in the liquid in the well, the valve means adapted to alternately admit compressed air into said lower chamber and then into said eduction pipe, said valve means exhausting air from said lower chamber into the well during admission of air into the eduction pipe.
13. In apparatus for pneumatically pumping liquids from wells, a displacement chamber and an eduction pipe in communication therewith at its lower end, means for filling said chamber with liquid from the well to cover the lower end of said eduction pipe, means for admitting compressed air to the said chamber for discharging the liquid from the chamber into the eduction pipe, and means for supplying compressed air to the eduction pipe during the filling of the chamber with oil from the well to lift the oil in said pipe and discharge it from the well, the oil entering said eduction pipe during discharge thereof from said displacement chamber, continuing to lift the oil in said eduction pipe to continuously discharge it from the well after admission of air to the eduction pipe.
14. In apparatus for pneumatically pumping liquids from wells, a well casing, a pipe extending into said well casing and comprising a chamber having an upper part and a lower displacement part and an eduction pipe surrounded by said chamber and in communication therewith at its lower end, means for filling said chamber with liquid from the well to cover the lower end of said eduction pipe, hollow valve members in said first mentioned pipe between the upper and the lower parts thereof for admitting compressed air to the said displacement part and for discharging the liquid therefrom into the eduction pipe, means for releasing the pressure in the displacement chamber to permit entrance thereto of liquid from the well and means for substantially simultaneously admitting compressed air to the upper part of said eduction pipe to further lift liquid therein.
15. In apparatus for pneumatically pumping liquids from wells, a displacement chamber and an eduction pipe in communication therewith at its lower end, means for filling said chamber with liquid from the well to cover the lower end of said eduction pipe, means for admitting compressed air to the upper part of said eduction pipe to lift liquid therein, the oil entering said eduction pipe during discharge thereof from said displacement chamber, continuing to lift the oil in said eduction pipe to continuously discharge it from the well after admission of air to the eduction pipe.
16. In apparatus for pneumatically pumping liquids from wells, a well casing, a pipe extending into said well casing, a valve dividing said pipe into an upper part for the reception of compressed fluid and a lower chamber extending into the liquid in the well, and an eduction pipe positioned in said first mentioned pipe and terminating in said lower chamber, operating means for said valve to position it to admit compressed fluid into the lower chamber from a source of compressed fluid supply to force the liquid in said chamber upwardly in the eduction pipe and means for operating said valve to admit compressed fluid into the eduction pipe at a point below the level of the liquid which has been forced into said pipe by the compressed air of the lower chamber, whereby the liquid in the eduction pipe may be lifted to the top of the well, and means operable by said valve to release the pressure of the fluid in the lower chamber during the introduction of the compressed fluid to said eduction pipe.
17. Apparatus for pneumatically pumping liquids from deep wells comprising a displacement chamber positioned in the liquid at the bottom of the well, an eduction pipe communicating with said displacement chamber and extending to the top of the well, a valve positioned in the well adjacent the eduction pipe and displacement chamber said valve being connected to a source of fluid pressure and adapted to alternately connect first, said displacement chamber and then said eduction pipe with the source of compressed fluid and means including said eduction pipe for controlling the operation of said valve.
18. Apparatus for pneumatically pumping liquids from deep wells comprising a displacement chamber positioned in the liquid at the bottom of the well, an eduction pipe communicating with said displacement chamber and extending to the top of the well, a valve positioned in the well, and means extending to the top of the well for controlling the operation of said valve, said valve being

connected to a source of fluid pressure and
adapted to alternately connect first said dis-
placement chamber and then said eduction
pipe with the source of compressed fluid for
5 pumping the liquid out of the well.

In testimony whereof, I have hereunto af-
fixed my signature.
